UNITED STATES PATENT OFFICE.

REIFF EDWARD CHRIST, OF BLACKFOOT, IDAHO.

GAS TIMER FOR ENGINES.

Application filed August 6, 1927. Serial No. 211,146.

This invention relates to an indicator for determining the timing of the sparking relative to the pistons.

An object of the invention is the provision of a device which is adapted to be inserted within the usual spark plug opening in a cylinder head of an engine for determining the position of the piston during the firing stroke and when the compressed gases are 10 adapted to be ignited.

A further object of the invention is the provision of a device adapted to be applied to cylinders having various types of heads for indicating the position of a piston in the 15 cylinder when the ignition should occur on the compression stroke of the engine.

This invention will be best understood from a consideration of the following detailed description, in view of the accompanying drawings forming a part of this specification; nevertheless it is to be understood that the invention is not confined to the disclosure, being susceptible of such changes and modifications which shall define no material departure from the salient features of the 25 invention as expressed in the appended claims.

Figure 1 is a vertical section of an engine showing my indicator applied thereto,

Figure 2 is a plan view of the indicator,

Figure 3 is a vertical section of the indicator,

Figure 4 is a vertical section of a modified form of the indicator,

Figure 5 is a vertical section taken along the line 5—5 of Figure 4, and

Figure 6 is a horizontal section taken along the line 6—6 of Figure 4.

Referring more particularly to Figures 1 to 3, inclusive, an engine 10 is shown in section having a cylinder head 11, a cylinder 12 and a piston 13. In the cylinder head is provided the usual combustion chamber 14 having a threaded opening 15 into which is adapted to be screwed the usual spark plug.

A plug 16 having a threaded portion 17 and 45 a passage 18 is screwed into the threaded opening 15 until the enlarged or tool-gripping portion 19 forms a stop for further movement of the plug. The upper end of the passage 18 is provided with internal threads 50 into which is screwed a guide 21. The upper end of the guide, as shown at 22, is knurled in order to provide for the ready rotation of the sleeve or guide.

A rod 23 having a lower or angularly disposed portion 24 is slidably mounted in the

guide or sleeve 21. The free end of the angularly disposed portion is provided with a point 25 adapted to engage the top of the piston. The upper end of the rod 23 is connected to a barrel 23^a of a micrometer 26 of any well known type. The micrometer is provided with a knurled sleeve 27 which is adapted to be rotated for adjusting the micrometer. A pin 28 on the upper end of the micrometer is adapted to engage the lower end of an adjustable rod 29. This rod is clamped between the members 30 and 31 by means of screws 32 while the upper end of the supporting rod 33 is also clamped by the members 30 and 31. The lower end of the rod 33 is reduced and 70 threaded and screwed into a vertical passage in the plug 19.

The operation of my device thus described is as follows: The piston 13 is moved to the upper limit of a stroke and the point 25 is placed in engagement with the piston, as shown in Figure 1, and the micrometer is adjusted to register zero. At this time the rod 29 is moved down to the position shown in Figure 3 with the lower end of said rod in engagement with the lug 28. The piston is then lowered and if it is desired to set the timing device at .100" the micrometer is then adjusted until it registers the above notation and the rod 29 is moved until it engages the finger or lug 28. The piston then is returned slowly and carefully until it comes into engagement with the point 25 whence the timing gear may be so adjusted that the spark will occur at this position of the piston. The operator readily determines when the piston engages the point 25 by the fact that the piston will resist further upward movement when engaged, care must be taken, however, to prevent any rapid movement during such operation.

Referring more particularly to Figures 4 to 6, inclusive, it will be seen that a modified form of the arrangement is produced for determining the timing of the piston 40 movable in the cylinder 41. In this case the threaded opening 42 for the spark plug is located at one side of the cylinder and through this threaded passage is screwed a hollow plug 43 having a longitudinal passage 44 therethrough. A rod 45 is pivoted, at 46, in the plug 43 and a spring 47 is adapted to maintain the outer free end of the rod 45 in an upward position so that the point 48 of the bent end 49 of the rod will contact with the top of the piston 40.

A rod 50 is pivotally connected, at 51, to the outer end of the rod 45 and has at its lower end a micrometer 52 of any well known type. The lower end 53 of the micrometer is adapted to contact at predetermined times with a stop rod 54 carrying a pair of brackets 55 which are clamped to the rod and also to a rod 56 by means of set screws 57. The upper end of the rod 56 is bifurcated, as shown at 58, which is adapted to receive a post 59. The split arms 60 and 61 of the upper end of the rod 56 are clamped together on the post 59 by means of set screws 62, the post 59 being screwed into a threaded passage in the plug 43 so that it will extend horizontally from the plug.

In the operation of the device shown in Figures 1 to 6, inclusive, the point 48 is placed in engagement with the upper face of the piston 40 when said piston is in its uppermost position and the micrometer is so adjusted that it will register zero and the stop or bar 54 is moved into engagement with the micrometer. The piston 40 is then lowered and whatever micrometer adjustment is desired by the manufacturer of the timing device is then registered on the micrometer 52 by turning the same until the proper number is indicated. At this time the point 48 is lowered and the piston 40 is returned until it engages the point 48 whence the timing device may be set for permitting the current to pass through the spark plug connected with the cylinder 41 at the proper time.

I claim:

- 35 1. A device of the character described comprising a contact rod having a pointed end adapted to contact with a piston of an internal combustion engine, a micrometer mounted on the other end of the rod, and an adjustable rod adapted to be engaged by the micrometer for determining the position of the contact rod, and means for supporting the contact rod and the adjustable rod on the engine.
- 40 2. A device of the character described comprising a contact rod having a pointed end adapted to contact with a piston of an internal combustion engine, a micrometer mount-

ed on the other end of the rod, an adjustable rod adapted to be engaged by the micrometer for determining the position of the contact rod, a plug, the contact rod being movable in the plug, and a support carried by the plug and connected with the adjustable rod for retaining the adjustable rod in a predetermined position on said engine.

3. A device of the character described comprising a contact rod having a pointed end adapted to contact with a piston of an internal combustion engine, a micrometer mounted on the other end of the rod, an adjustable rod adapted to be engaged by the micrometer for determining the position of the contact rod, a plug, the first mentioned rod being movable in the plug, a support carried by the plug and connected with the adjustable rod for retaining the adjustable rod in a predetermined position on said engine, and a spring for holding the pointed end of the rod away from the piston.

4. A device of the character described comprising a contact rod having a pointed end adapted to contact with a piston of an internal combustion engine, a micrometer mounted on the other end of the rod, an adjustable rod adopted to be engaged by the micrometer for determining the position of the contact rod and supported on said engine, the micrometer having pivotal connection with the contact rod, and means for supporting the contact rod on the engine in a predetermined position.

5. A device of the character described comprising a contact rod having a pointed end adapted to contact with a piston of an internal combustion engine, a micrometer mounted on the other end of the rod for determining the position of the contact rod, an adjustable rod adapted to be engaged by the micrometer, a plug, the contact rod being movable in the plug, a support carried by the plug and connected with the adjustable rod for retaining the adjustable rod in a predetermined position on said engine, and means for clamping the adjustable rod to the support.

REIFF EDWARD CHRIST.
